Anthony F. Leis, Shore Road, Oakdale, N.Y.

Filed Jan. 11, 1960, Ser. No. 58,990

Term of patent 14 years

(Cl. D31—4)

Fig. 3.

Fig. 1 is a front perspective view of a fishing rod support showing our new design;

Fig. 2 is a left side elevational view; and

Fig. 3 is a top plan view thereof, the bottom being substantially the same with the exception that the bottom of the rod holder is not flared.

We claim:

The ornamental design for a fishing rod support, substantially as shown and described.
